CLAIM

The ornamental design for a laboratory device, as shown and described.

DESCRIPTION

FIG. 1 is a front perspective of a first embodiment of a laboratory device, with the lid thereof in an open configuration showing an air spring arm, hinge, condenser, and microscope stage;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan thereof;

FIG. 7 is a bottom plan of the laboratory device of FIG. 8 with the lid in the open configuration;

FIG. 8 is a front perspective of a second embodiment of a laboratory device, with a lid thereof in an open configuration showing an air spring arm, condenser, and microscope stage;

FIG. 9 is a front elevation view thereof;

FIG. 10 is a rear elevation view thereof;

FIG. 11 is a right elevation view thereof;

FIG. 12 is a left elevation view thereof;

FIG. 13 is a top plan thereof; and,

FIG. 14 is a bottom plan of the laboratory device of FIG. 15 with the lid in the open configuration.

The broken lines in the drawings depict portions of the laboratory device that form no part of the claimed design.
